KEYBOARD CLEARING MECHANISM

Herman Gang, Livingston, N. J., assignor to Monroe Calculating Machine Company, Orange, N. J., a corporation of Delaware

Application September 13, 1950, Serial No. 184,664

3 Claims. (Cl. 235—79)

1

The invention relates to keyboard clearing means for calculating machines having control means manually settable to enable or disable such clearing means. More specifically, the invention relates to means automatically operable to set such manually settable control means.

In certain machine operations involving plural registration of a value set on the keyboard, as for example programs of multiplication or division, it is obviously necessary to insure that the control means for the clearing or non-repeat means is disabled, i. e., adjusted to repeat position. However, certain series of such calculations are often interspersed with single registering operations. It therefore becomes necessary to re-enable the non-repeat means for each of these single operations.

The present invention provides simplified and improved means for automatically adjusting manually adjustable control means for the clearing means to repeat position upon initiation of a machine operation involving plural registration; in conjunction with automatic means for adjusting such control means to non-repeat or enabling position upon conclusion of the operation. The devices of the invention, however, are ineffective to adjust the control means to non-repeat position upon conclusion of the plural registering operation if, upon initiation of such operation, the control means has been manually set previously to repeat position. Thus, it will be seen that at the conclusion of the calculation the manual setting of the control means will be unchanged from its previous set position.

The invention, however, will best be understood from the following description with reference to the accompanying drawings in which:

Fig. 1 is a right side elevation of a calculating machine showing the control devices of the invention set to non-repeat position;

Fig. 2 is a fragmentary right side elevation showing the control devices set to repeat position by the manually operable means;

Fig. 3 is a view similar to Fig. 2 showing the control devices set to repeat position by the automatically operable means;

Fig. 4 is a fragmentary vertical section taken through the keyboard;

Fig. 5 is a fragmentary view showing in detail the latching means for the keys shown in Fig. 4;

Fig. 6 is a fragmentary plan view showing details of the keyboard clearing mechanism.

The invention has been disclosed as controlling the operation of keyboard clearing means in conjunction with the performance of a program of

2

multiplication or of division in a calculating machine operating in accordance with the disclosure of applicant's Pat. #2,531,207. This machine is disclosed in applicant's Pat. #2,531,206 as having manually settable control means for selectively enabling or disabling the keyboard clearing means to provide for a single or for a multi-cyclic registering operation respectively upon depression of a plus or of a minus bar. According to the present invention this manually adjustable control means for the clearing means is so modified in structure as to be alternatively adapted for the aforesigned automatic adjustments.

The keyboard 1 (Fig. 1) comprises a plurality of denominational columns of spring retracted depressible value keys 3 (Figs. 4 and 5). Each of the columns is provided with a spring urged latching bail 5 for holding the keys of the related column in depressed or set position by engagement with a notch 3' in the stem of the depressed key. Selection bails 7 are adjustable in accordance with depressed keys 3 to adjust the digital actuators 8 accordingly. Thus, upon each registering cycle of the machine, values set on the keyboard are registered in dividend-product register 11.

The keyboard clearing means includes a transversely disposed slide 13 (Figs. 4 and 6) which engages each of the latching bails 7 and upon movement by bell-crank 15 operates to rock each of the bails, thereby releasing any set keys 3 on the keyboard.

A unitary member comprising a control plate 17 (Figs. 1, 2, and 3) pivotally mounted on shaft 19 is selectively adjustable to enable or alternatively disable the keyboard clearing means. With plate 17 in clockwise position (Fig. 1), a shoulder 17' thereof engages a toe at the lower end of an arm 21 thereby moving and holding the lower end of the arm to the right on its slot and pin mounting 22. This adjustment of arm 21 brings a cam face 21' thereof into the path of movement of a cam 23 which is driven in time with the registering mechanism through a gear train 25. Cam 23 is driven by lost motion connection so that near the end of each registering cycle, either forwardly or reversely, said cam engages and rocks arm 21 counterclockwise. A second arm 27 has common pivotal mounting at its lower end with arm 21 and slot and pin connection near its upper free end. Thus, arm 27 is rocked with arm 21 and its upper free end engages and rocks bell crank 15 clockwise (Fig. 6) to move slide 13 thereby rocking bails 5 and releasing depressed value keys 3 of the keyboard.

In certain operations, fully disclosed in applicant's aforesaid Pat. #2,531,206, arm 27 is raised with relation to arm 21 so that its upper free end is moved ineffectively above bell-crank 15 thus disabling the clearing means with control plate 17 set in effective clockwise position. These operations, however, bear no relation to the present invention and therefore arms 21 and 27 may be considered as a unit with pin and slot mounting at its lower end.

With control plate 17 adjusted to counterclockwise or disabling position (Fig. 2), shoulder 17' will be removed from engagement with the toe of arm 21. Therefore, when cam 23 engages face 21' of arm 21, the lower end of the arm will be moved to the left and the upper operating end of arm 27 will be imparted no movement to rock bell-crank 15 to clear the keyboard. Thus, the values set on the keyboard will be repeatedly registered upon plural operation of the registering mechanism.

Manually settable means comprising repeat key 29 and non-repeat key 31 are provided to effect the respective adjustments of control plate 17. The lower end of the stem of non-repeat key 31 has direct pivotal connection with plate 17 and repeat key 29 is connected therewith through auxiliary plate 33. Auxiliary plate 33 has common pivotal mounting with control plate 17 and yieldable connection therewith comprising a spring 35. Spring 35 urges control plate 17 clockwise and auxiliary plate 33 counterclockwise, with a pin 33' on plate 33 normally engaging a shoulder of plate 17 to limit the relative movement. Pin 33' is further utilized to provide pivotal mounting for the lower end of the stem of repeat key 29. Depression of non-repeat key 31 will adjust plates 17 and 33 clockwise (Fig. 1) as a unit thereby enabling the clearing mechanism and conversely depression of repeat key 29 will rock the plates counterclockwise (Fig. 2) to disable the clearing mechanism. A toggle spring 37 having pin attachment to the machine frame and to an upwardly extending forked arm of auxiliary plate 33 holds the plate in either of its adjusted positions and normally control plate 17 will be held in like adjusted position therewith. The pin providing the attachment of toggle spring 37 with the machine frame is positioned between the fork of the arm of auxiliary plate 33 and the inner sides respectively of the fork by engagement therewith limit the movement of the plate to its adjusted positions.

Should plates 17 and 33 be set in clockwise non-repeat or enabling position by depression of non-repeat key 31, control plate 17 may be automatically set counterclockwise (Fig. 3) to disabling or repeat position without disturbing the setting of auxiliary plate 33. Such independent adjustment of control plate 17 is permitted by the yieldable spring connection 35 the tension of which is not sufficient to overcome the urge of toggle spring 37 holding auxiliary plate 33 in its clockwise setting.

The automatic and independent adjustment of control plate 17 may be effected in conjunction with operations incident to the initiation of programs of division or multiplication fully disclosed in the aforesaid Pat. #2,531,207. According to said disclosure to which reference is made for the operational and structural details, a shaft 39 (616 in the patent) is rocked from the clockwise position (Figs. 1 and 2) to the counterclockwise position (Fig. 3) as an incident to

the initiation of a program of division upon depression of a divide key, not shown. Shaft 39 remains in counterclockwise position until the conclusion of the division program, at which time it is restored clockwise to normal.

A depending arm 41 fixed on shaft 39 is adapted to engage a lug at the free rear end of a link 43 which at its forward end has pivotal connection with a depending arm of control plate 17. Therefore, upon counterclockwise movement of shaft 39 (Fig. 3) arm 41 will engage link 43 thereby moving said link toward the rear of the machine and adjusting control plate 17 counterclockwise against the tension of spring 35 to disable the keyboard clearing mechanism during the program of division. As heretofore noted, auxiliary plate 33 will be held in opposed adjusted position by toggle spring 37 and thus spring 35 will be rendered effective to urge control plate clockwise to non-repeat position against the restraint of link 43, arm 41, and shaft 39. Therefore, upon clockwise movement of shaft 39 and arm 41 at the conclusion of the division program, link 43 will be released and spring 35 will then restore control plate clockwise into non-repeat position and into normal relation with auxiliary plate 33, as shown in Fig. 1. Should the repeat key 29 be set (Fig. 2) upon initiation of the division program, arm 41 will be idly operated in the division operation and no relative adjustment will be effected between control plate 17 and auxiliary plate 33. Therefore, at the conclusion of the division program, control plate 17 will remain in the repeat position to which it was manually adjusted.

Upon initiation of a program of multiplication a setting slide 44 (593 in the noted Pat. #2,531,207) is moved to the rear through connecting linkage upon depression of multiplier key 45. Slide 44, key 45, and the connecting parts are latched in set position during the program and at the conclusion are released and spring retracted as fully disclosed in the patent. An upstanding finger 44' of slide 44 engages a pin 17a of control plate 17 in its rearward movement thereby adjusting the plate to repeat position if manually set to non-repeat, and the subsequent restoring adjustments at the conclusion of the multiplication program are all effected as described in connection with the division program.

As disclosed in the aforesaid Pat. #2,531,206, a second means, independent from that herein described in connection with the devices of the invention is provided to clear the keyboard. This operation is effected by a clear clutch which rocks a bail to depress a zero key of each column of the keyboard thereby releasing any set value keys. As disclosed in the aforesaid Pat. #2,531,207, operation of this keyboard clearing means is effected automatically at the conclusion of either a program of multiplication or of division. Values may, therefore, be set in the keyboard for the following registering operation without the necessity of a preclearing operation.

It will be noted that the devices of the invention may be rendered inoperative by replacing spring 35 by another sufficiently tensioned to overcome toggle spring 37 should it be desired that the clearing means remains disabled at the conclusion of the division or multiplication programs. This arrangement offers considerable advantage by permitting the use of identical parts adaptable for alternative operation without extensive alteration.

Although a preferred embodiment of the invention has been disclosed, it will be understood that the invention is not to be restricted except in so far as necessitated by the spirit of the appended claims.

I claim:

1. In a calculating machine having a register, a keyboard comprising settable numeral keys, and means for latching said keys in set position; the combination with a member settable upon initiation of a machine operation involving plural registration of a value set on said keyboard in said register and means for automatically restoring said member upon conclusion of said operation; of non-repeat means automatically operable to release said keys from said latching means, a control device adjustable alternatively to enable or to disable said non-repeat means, alternatively settable non-repeat and repeat keys for effecting the adjustments respectively of said device, a yieldable connection between said device and said repeat key, a power transmission member operable by said settable member upon initiation of said machine operation to move to and then to hold said device in disabling position, means for holding said repeat key in unset position against the urge of said yieldable connection, and means comprising said yieldable connection for adjusting said device to enabling position upon release thereof by restoration of said settable member.

2. In a calculating machine having a register, a fixed frame, a keyboard comprising settable numeral keys on said frame, and means for latching said keys in set position; the combination with a member settable upon initiation of a machine operation involving plural registration of a value set on said keyboard in said register, and means for automatically restoring said member upon conclusion of said operation; of non-repeat means automatically operable to release said keys from said latching means, a control device adjustable alternatively to enable or to disable said non-repeat means, alternatively settable non-repeat and repeat keys for effecting the adjustments respectively of said device, a yieldable connection between said device and said repeat key, a toggle spring between said repeat key and said fixed frame operable to hold said repeat key in either set or unset position, a power transmission member operable by said settable member

upon initiation of said machine operation to move and then to hold said device in disabling position with said repeat key in unset position, and means comprising said yieldable connection for adjusting said device to enabling position upon release thereof by restoration of settable said member.

3. In a calculating machine having a register, a fixed frame, a keyboard comprising settable numeral keys on said frame, and means for latching said keys in set position; the combination with a member settable upon initiation of a machine operation involving plural registration of a value set on said keyboard in said register, and means for automatically restoring said member upon conclusion of said operation; of non-repeat means automatically operable to release said keys from said latching means, a control plate having pivotal mounting on said frame and adjustable alternatively to enable or to disable said non-repeat means, an auxiliary plate having common pivotal mounting with said control plate and yieldable connection therewith, a non-repeat key having operating connection with said control plate, a repeat key having operating connection with said auxiliary plate, a toggle spring between said auxiliary plate and said frame normally effective to hold said control plate in either of its adjusted positions, a power transmission member operable by said settable member upon initiation of said machine operation to move and then to hold said control plate in disabling position with said auxiliary plate held in the opposed position by said toggle spring, and means comprising said yieldable connection for adjusting said device to enabling position upon release thereof by restoration of said settable member.

HERMAN GANG.
